RESETTING GAUGE FOR INTERNAL SCREW THREAD CUTTERS

Charles H. Sapper, Brooklyn, N.Y.

Application January 18, 1944, Serial No. 518,689

4 Claims. (Cl. 33—185)

This invention relates to a device for resetting a cutting tool for recutting internal screw threads.

In recutting an internal thread because it is mashed, imperfect, worn, or for any reason, it is necessary to reset the cutter in the lathe or thread cutting machine. This makes it necessary to back the cutter away from the work by releasing the carriage from the feed screw and to release the cutter from the tool post on the carriage and then reset the cutter. The resetting of the cutter under these conditions is difficult and without assurance that the cutter is reset with accuracy or in proper registry for the thread recutting operation.

The principal object of the present invention is the provision of a device of the character mentioned which will enable the resetting of a thread cutting tool quickly, easily and accurately to the end that a thread may be properly recut to the desired or required size and pitch.

The nature of the invention and its distinguishing features and advantages will appear when the following specification is read in conjunction with the accompanying drawing, in which:

Fig. 1 is a top plan view of the device of the present invention in use and the work in which an internal thread is to be recut is shown partly in section.

Fig. 2 is a transverse sectional view taken on the line 2—2 of Fig. 1.

Fig. 3 is a perspective view of the gauge clamp per se.

Fig. 4 is a sectional view taken on the line 4—4 of Fig. 3.

Referring now more particularly to the drawing, it will be apparent the device generally stated consists of a gauge member or template 10 and a clamp 11 for holding the gauge member 10 in place with respect to a piece of work 12 to enable the resetting of a thread cutting tool 13.

The gauge member 10 consists of an elongated flat piece of metal having teeth 14 formed on one longitudinal edge. The teeth 14 correspond to the conventional standard V thread. Teeth 15 are formed on the other longitudinal edge of the member 10 and these teeth have slightly straight or rounded tops and bottoms and in other respects correspond to the teeth 14. The teeth 15 so formed are adapted to seat more perfectly in contact with inaccurate or deformed threads.

The clamp 11 includes cooperative clamping parts or members 16 and 17 respectively, the part 17 being slidably related to the part 16 by means

of a slide 18 slidable on the part 16. The part 16 is of angular formation or L shape to provide portions 19 and 20 respectively. The portion 19 is U shape in cross-section and merges into the portions 20. The portions 20 are spaced to accommodate the gauge member 10 therebetween. A pin 21 is supported by the portions 20 between the same and serves to engage between two of the teeth 14. The slide 18 is slotted to receive the portion 19 of the part 16 and carries pins 22 offset with respect to each other and engageable with the opposite longitudinal sides respectively of said portion 19 to cause the slide to ride smoothly along the portion 19 to different positions of adjustment with respect to the part 16. The pins 22 also prevent the slide 18 from becoming cocked when the screw 23 is manipulated to set up the clamping action. The clamping part 17 has a screw 23 swivelly connected therewith as 20 at 24. The screw 23 is in threaded engagement with the slide 18. One end 25 of the part 17 is reduced and projects into the groove provided by the portion 19 in order to prevent the part 17 from turning. The part 17 is of U shape in 25 cross-section to afford a good grip on the work, especially when it has a cylindrical surface as shown in the present instance with respect to the work 12.

The gauge member or template 10 in association with the clamp 11 extends between the portions 20 of the part 16. The gauge member may be adjusted or set in any satisfactory relation to the part 16 to project partly interiorly of the tapped bore in the work and partly exteriorly thereof, as shown in Fig. 1. The gauge member 10 is placed in accurate registry in which the teeth 15 are brought into meshing contact with the threads of the work. The pin 21 is engaged between two teeth 14 in contact therewith to impose pressure on the gauge member 10 when it is clamped. The clamping action is effected by moving the slide 18 along the portion 19 to bring the clamping part 17 into contact with the work 12. The screw 23 is then manipulated to set up a clamping action of the part 17 in conjunction with the pin 21. The gauge member 10 is thus securely held in the tool resetting position. The cutter 13 which has been drawn clear of the work is made loose in the tool post. The carriage on which the tool post is mounted is adjusted to bring the point of the cutter between two of the teeth 14 on the exteriorly projecting portion of the gauge member 10 in proper registry. The cutter 13 is then secured on the tool post in the registered position resetting the

cutter for the thread recutting operation. It is of course understood the device will be removed from the work in order that the recutting operation may be carried out.

Concerning the clamp shown in the present instance, the part 18 being adjustable on the part 16, enables the device to be quickly positioned on the work of different sizes. It is to be understood the clamp may be made with the part 16 having a tapped lug integral therewith in lieu of the part 18.

It will be obvious there is described a device which aids a machinist in cutting threads with a machine tool, because it is possible to reset the cutter accurately to recut the thread if the thread is faulty due to the hardness or toughness of the material, and in case a cutter breaks or becomes dull or wears off before the thread has been finished.

I claim:

1. A device for resetting a screw thread cutter comprising a gauge member consisting of an elongated flat piece of metal having teeth on each of its longitudinal edges to correspond to

standard screw threads, the teeth on one edge to accurately contact screw threads to be recut and the teeth on the other edge to enable the cutter to be reset by engaging some of the teeth last mentioned for the thread recutting operation, and means to secure said gauge member in the resetting position.

2. A device as set forth in claim 1, wherein said means consists of a clamp.

3. A device as set forth in claim 1, wherein said means includes cooperative clamping parts, and the gauge member is adjustably engaged with one of said parts.

4. A device for resetting a screw thread cutter comprising a gauge member having teeth formed to accurately contact screw threads to be recut and when so placed to enable the cutter to be reset in contact therewith for the thread recutting operation, and means to secure said gauge member in the resetting position, said means including a clamping part having a portion to engage the gauge member.
